UNITED STATES PATENT OFFICE

HERBERT A. WOOLEVER, OF ORANGE, PENNSYLVANIA

NUT WRENCH

Application filed April 29, 1929. Serial No. 358,924.

My invention relates to an improvement in wrenches, particularly to that type in which the movable jaw is actuated by a relatively movable nut and screw, the nut being segmental and releasable to temporarily disconnect the same from the screw, allowing the movable jaw to be readily moved to its approximate position, whereupon the nut is again connected to the screw and a tight adjustment is made thereby.

Wrenches of this general class have heretofore been known but the release mechanism of these devices have certain faults which prevent the same from being placed in general use, and it is the object of this invention to improve the construction of such mechanism to produce a wrench that is strong and durable, yet being capable of quick manipulation for the purpose of the function above expressed, such construction involving as few parts as practical and these being assembled in such a manner as to prevent the same from being displaced during rough and continued usage.

Further objects of my invention reside in the construction of the slide that carries the loose or releasable half of the split nut, as well as the means for guiding this slide.

Still another object of my invention lies in the provision of a catch that positively holds the split nut in or out of engagement with the screw, being especially useful on large and heavy wrenches, as in these wrenches there is a tendency for the split half of the nut to become displaced.

Other objects of my invention will be apparent from the following description of my preferred embodiment, taken in connection with the accompanying drawings, in which:—

Figure 1 is a side view of a wrench constructed in accordance with my invention.

Fig. 2 is a similar view, partly in section,

Fig. 3 is an enlarged detail view, illustrating the construction of the movable jaw and split nut,

Fig. 4 is a view similar to that of Fig. 3, being partly in section and including the nut slide,

Fig. 5 is a sectional view taken on line 5—50 of Fig. 1.

Fig. 6 is a sectional view taken on line 6—6 of Fig. 4.

Fig. 7 is a sectional view taken on line 7—7 of Fig. 1, and

Fig. 8 is a modification of my invention, 55 showing the release mechanism as being applied to an automobile wrench.

Like numerals of reference represent like parts throughout the several views of the drawings.

Figs. 1 to 7 of the drawings illustrate the invention in connection with a monkey wrench, comprising the fixed jaw 1, at the upper end of shank 2, movable jaw 3 slidable on the shank, screw bearing 4, and handle 5 slipped on the reduced end of the shank and held in place against the usual abutment by means of the clamping nut 6. The general construction of the movable jaw is illustrated in Fig. 3, being of integral form and including the jaw proper 7, a downwardly extending member 8, and lower brace member 9, the jaw and brace member being slotted to slidably receive the aforementioned shank 2, and the downwardly extending member having 70 a bore 8a to loosely receive the customary screw 10 and cut away to form the plain half of the split nut, as more clearly disclosed in Figs. 4 and 5. The other or threaded half 75 11 of the split nut is received in said cut away portion and is secured to a nut slide as by rivets 12, said slide comprising two U-shaped straps 13 13a of sheet metal, and as shown in Fig. 5 the former is bent around the nut and brace member of the movable jaw, with

the upper and lower portions 13b extending to the rear thereof, while the strap 13a joins these rearwardly extending end portions exteriorly overlapping the same and being riveted thereto, as shown in Fig. 4. Since the medial portion of strap 13a is spaced from the said shank 2 and brace member 9 the slide may be moved to the left to thereby open the split nut and release the screw 10. However as the said nut should normally be connected to the screw a spring 14 on guide pin 15 is provided to yieldably keep the slide in its position to the right, with the nut closed, and to positively maintain the slide in this position, a spring catch 16 is provided, said 100

catch also serving to temporarily hold the split nut disengaged as shown in Fig. 2. It will be noted by reference to Fig. 4 that the spring catch is secured, by welding or otherwise, to the lower edge of the brace member 9 of the movable jaw so that the engaging projection or hump 16a of said catch will engage the lower edge of the rear strap 13a to hold the half nut in either position to which it is moved. In the case of small wrenches this catch is not necessary, but when my invention is applied to large heavy wrenches it is particularly useful for reasons as aforesated. To properly guide the slide as well as hold the same with relation to the movable jaw I provide a narrow U-shaped guide strap 17 bent around or conforming to the rear portion of the aforementioned brace member and secured thereto as by rivets 18. The ends of the front strap 13 of the slide are rearwardly slotted to receive this guide strap and provide the extensions 13b as is readily apparent. In this connection it will be noticed that the overlapping ends of the rear strap 13a not only brace the front strap 13 but also lie adjacent and overlap the guide portions of strap 17 forming a rigid and easily workable structure. The function of the screw 10 is the same as in any ordinary monkey wrench, being turned by collar 10a fixed thereon to move the half-nut and carry the movable jaw back and forth.

In Fig. 8 I have disclosed my invention as being applied to an automobile or machinist's wrench, a similar release mechanism being used. In this instance the shank 19 of the fixed jaw 20 is provided with the usual teeth 21, and has slidably received thereon the usual movable jaw 22. In this embodiment I have provided the forward slide strap 23, the rear attached strap 24, and guide strap 25, all constructed and arranged to function as described in connection with Figs. 1 to 7, including the spring and catch or the spring alone. It will be noticed however that the front strap 23 in this form of my invention instead of carrying one-half of a split nut carries a screw 26 which is adapted to cooperate with the aforementioned teeth to actuate the movable jaw.

In operating my improved wrench to adjust the position of the jaws with respect to the nut or other object to be manipulated the connected strap members 13-13a carrying the movable threaded member of the split nut is slid upon the guide members 17-17 at opposite sides of the movable jaw to disengage said threaded member from the screw 10, and the strap member 13a riding over the hump on the spring catch 16 will be held by the latter in this position so that the movable jaw may be readily adjusted on the shank to an approximate position with relation to the nut to be manipulated. When the catch is released for engagement of the threaded

member 11 of the nut on the wrench with the screw 10 the latter may be turned for closer adjustment in the usual manner, during which adjustment the catch serves to hold the member 11 in positive engagement with the adjusting screw. 70

Having fully described my invention in connection with the preferred illustrative embodiments I do not desire to be limited thereto but wish to be protected by the spirit and scope of the appended claims. 75

I claim:

1. A wrench comprising an elongated shank having a handle at one end and a fixed jaw at the other end, a movable jaw slidable on the shank with respect to the fixed jaw, and cooperating threaded members one of which is carried by the shank and the other by the movable jaw, the member carried by the jaw being movable to and from the companion member for engagement therewith to slide the movable jaw on the shank; together with means for operating the movable threaded member consisting of a metal strap secured thereto and embracing the movable jaw with a connecting portion at the rear ends of the strap beyond the rear end of the movable jaw and the sides of said strap provided with slots, a strap extending around the rear end of the movable jaw to which it is attached and having the ends thereof located in the aforesaid slots to form guides for the strap carrying the movable threaded member, a spring interposed between the connecting portion of the first mentioned strap and rear end of the movable jaw to move the parts to normal position with the threaded members of the wrench in engagement with each other, and a spring catch secured to the movable jaw and engaging the connecting portion of the strap carrying the movable member of the nut to hold said strap in either position to which it is shifted. 90 95 100 105

2. A wrench comprising an elongated shank having a handle at one end and a fixed jaw at the other end, a movable jaw slidable on the shank with respect to the fixed jaw, and cooperating threaded members one of which is carried by the shank and the other by the movable jaw, the member carried by the jaw being movable to and from the companion member for disengagement therewith to slide the movable jaw on the shank; together with means for operating the movable threaded member consisting of a U-shaped metal strap the bight portion of which is secured to said member and the ends thereof bifurcated and extended beyond the rear end of the movable jaw, a metal strap connected to the ends of the aforesaid strap to form a crosspiece spaced from the rear end of the movable jaw, a U-shaped strap attached to the movable jaw with its ends between the branches of the bifurcated portions of the aforesaid strap to form 110 115 120 125 130

guides therefor, a spring interposed between the movable jaw and cross piece of the strap carrying the movable threaded member of the wrench, and a spring catch secured to the movable jaw and having a hump engaging the movable strap to hold said strap in either position to which it is shifted in engaging and disengaging the threaded member of the split nut with the screw of the wrench.
